UNITED STATES PATENT OFFICE

91,233

DESIGN FOR A MEMORANDUM DEVICE

Cass Connaway, Albany, N. Y.

Application October 17, 1933. Serial No. 49,506

Term of patent 14 years

To all whom it may concern:

Be it known that I, CASS CONNAWAY, a citizen of the United States, residing at Albany, county of Albany, and State of New York, have invented a new, original, and ornamental Design for Memorandum Device, of which the following is a specification, reference being had to the accompanying drawing which is a perspective view of the device.

I claim:

The ornamental design for a memorandum device as shown.

CASS CONNAWAY.
